Edgar V. Vetter

UNITED STATES PATENT OFFICE.

ROBERT FORESMAN, OF MONTCLAIR, NEW JERSEY.

SOUND-REPRODUCING RECORD.

1,356,815.

Specification of Letters Patent. Patented Oct. 26, 1920.

Application filed January 25, 1919. Serial No. 273,114.

To all whom it may concern:

Be it known that I, ROBERT FORESMAN, a citizen of the United States, and residing at Montclair, in the county of Essex and State 5 of New Jersey, have invented certain new and useful Improvements in Sound-Reproducing Records, of which the following is a specification, such as will enable those skilled in the art to which it appertains to make 10 and use the same.

This invention relates to sound reproducing records and particularly to such devices as are used in connection with talking machines, phonographs, graphophones and the 15 like; and the invention consists of an improved mounting or holder for records of this class, preferably made in the form of a book, the construction of which is similar to that of a box to and within which one or 20 more sound records are applied or secured; a further object of the invention being to secure to or place the sound records on the inner face of the separate members of the book-shaped holder, and provide the outer 25 face of the separate box members with stories which correspond with the subject upon the record; a still further object being to provide the outer face of one part of the box with a story which corresponds with the 30 subject of the record secured to the inner face of the other part of the box member; and with these and other objects in view the invention consists in a device or devices of the class and for the purpose specified, constructed and operating as hereinafter 35 described and claimed.

The invention is fully disclosed in the following specification, of which the accompanying drawings form a part, in which the 40 separate parts of my improvement are designated by suitable reference characters in each of the views, and in which:—

Figure 1 is a sectional view of a bookcase or cabinet showing a number of my im- 45 proved book-shaped box members mounted therein;

Fig. 2 a perspective view of one of the book-shaped box members detached;

Fig. 3 a section on the line 3—3 of Fig. 2 50 and on an enlarged scale;

Fig. 4 an inside view of one part of the book-shaped box member shown in Figs. 2 and 3;

Fig. 5 an inside view of the other part of 55 the book-shaped box member shown in Figs. 2 and 3; and,

Fig. 6 an outside view of that part of the book-shaped box member shown in Fig. 4.

One of the objects of my invention is to provide a record holder or container of the 60 class specified which can be packed or arranged in a cabinet in the manner of books or in the form of a library and in Fig. 1 of the drawing, I have indicated at 10 the side walls of a bookcase, or the side walls of the 65 cabinet of a sound reproducing machine of any kind or class, and at 11 I have indicated two shelves of a bookcase or cabinet on one of which is shown supported nine volumes 70 of my improved book-shaped box members 12, which constitute a part of what I call a talking library.

The book-shaped box members 12, one of which is shown in detail in Figs. 2 to 6 inclusive, consists of separate parts 13 and 14. 75 The part 13 comprises a rectangular portion 15 provided at one side with a beaded edge portion box member, and at its other three sides with raised flanges 17 set inwardly of said edge portion as clearly shown in Figs. 80 3 and 4 of the drawing. The part 14 of the book-shaped box member comprises a rectangular portion 18, one side edge of which is provided with a raised flange 19 and the other three side edges of which are pro- 85 vided with raised flanges 20 set inwardly from said side edges and the dimensions of the part 14 of the box member, between the flange 19 and the opposite flange 20 thereof is less than the dimensions of the part 13 of 90 the box member between the beaded portion 16 and the opposite side flange 17 thereof, so that the flanges 19 and 20 of the part 14 of the box member will fit within the bead 16, or the inner wall 21 thereof, and the flanges 17 of the part 13 of the box member as clearly illustrated in Fig. 3 of the drawing. 95

The above described construction forms the book-shaped box member 12 which in all respects is of general book form, the 100 covers of which are made up of the rectangular portions 15 and 18 of the parts 13 and 14, while the bound end of the book is formed by the beaded portion 16 and, in practice, I provide the rectangular portions 105 15 and 18 of the parts 13 and 14 of the box member 12 with central apertures 22 and 23, and secured to the inner faces of said rectangular portions are sound reproducing records 24 and 25 respectively, the apertures 26 of which are in common alinement with the apertures 22 and 23.

2
In the accompanying drawing, the subject of the record 24 is indicated as being "The Mocking Bird" as is illustrated at 27 on the top face of the record, as shown in Fig. 4, while the record 25, or the subject thereof, pertains to "Mother Goose" as is indicated by its title on the face of the record as shown at 28 in Fig. 5 of the drawing.

I also preferably secure to, or apply to, 10 the outer faces of the rectangular portions 15 and 18 of the separate parts of the box member 12 in any desired manner printed as well as illustrated subject-matter pertaining to the subjects upon the records 24 15 and 25, and in Fig. 2 of the drawing I have indicated at 29 on the outer face of the rectangular portion 18 of the part 14 of the box member, a story of the "Mocking Bird" which is also illustrated, while in 20 Fig. 6 I have indicated at 30 the story of "Mother Goose" which is placed in, or applied to, the outer face of the rectangular portion 15 of the part 13 of the box member in any desired manner. From the foregoing 25 it will be noted that the subject upon the record 24 on the part 13 of the box member is printed or otherwise placed upon the part 14 of the box member, while the subject of the record 25 in the part 14 of the box member is printed or otherwise placed upon the part 13 of the box member, and the reason for this arrangement of the various subjects used in connection with or on my improved record holder permits a child or any other 30 party to read, sing or to note in any way by words, music or illustrations on one part of the book-shaped box member, the subject played by a sound reproducing machine on the record in or on the other part 35 of the book-shaped box member. As shown in Figs. 1 and 2 of the drawing, I also preferably mark the separate book-shaped box members for identification by "vol. 1, 2, 3," 40 etc., as shown at 31 and which is applied to the bound or beaded end 16 of the part 13 of the box member and upon said beaded end I also preferably apply or mark the title or titles of such volume which, as 45 shown at 32 in Fig. 2 of the drawing, is "Mother Goose" and "The Mocking Bird," and all of the volumes are also preferably marked at the bottom as shown at 33 in 50 Figs. 1 and 2 with the words "Talking library," which will identify my invention or my improved book-shaped box member which may be placed upon a shelf, or in a bookcase or cabinet, as is illustrated in Fig. 1, and serves to contain one or more records with or without the stories or other 55 illustrations of the subject of the records contained in said box member.

In other words, my invention is not necessarily limited to the combination of a

story of the subject of the record or records 65 contained in a book-shaped box member which is preferably printed or otherwise applied to the outer faces of the box member, and while I have shown a specific form and construction of book-shaped box member, it will be understood that various changes in and modifications of the details of construction herein shown and described may be made, within the scope of the appended claim, without departing from the 70 spirit of my invention or sacrificing its advantages.

Another decided advantage of my improved book-shaped box member, which serves as a container for records of the class 80 specified, lies in the fact that by mounting or securing the records centrally of said box member and leaving an extended and flanged edge on the box member entirely around and spaced from the periphery of 85 the record secured therein for the purpose of preventing the breaking of the record should said box member be dropped or handled roughly by the user.

It will also be understood that the subject 90 or story printed or otherwise illustrated on the outer face or faces of the separate parts of the box member may be reproduced exactly by the record, as for example, a story of "Mother Goose" as printed on the face 95 of one part of the box member may be told by the record or by playing the record in the other part of the box member, and it will be apparent that my improvement may be used for instructive purposes, for teaching children to sing, to tell stories and for numerous other purposes as well as to educate them in different languages, if desired; my invention being not limited to any specific subject placed upon or applied to the 100 separate parts of the box member or upon the records therein.

Having fully described my invention, what I claim as new and desire to secure by Letters Patent, is:—

110 A record holding device of the class described comprising a box-shaped member composed of detachably connected parts, one of said parts being provided on one face thereof with a reproducible record having a central aperture and the box wall being provided with a perforation which coincides therewith, whereby the record can be played without removing it from the box.

115 In testimony that I claim the foregoing 120 as my invention I have signed my name in presence of the subscribing witnesses this 24th day of January, 1919.

ROBERT FORESMAN.
